UNITED STATES PATENT OFFICE.

JOHN T. PHIPPS, OF HUNTINGTON PARK, CALIFORNIA.

PUMP JACK.

Application filed December 21, 1926. Serial No. 156,268.

This invention has to do generally with pump jacks or power heads for reciprocating the sucker rods of deep well pumps, and it is the general object to provide a pump 5 jack of the long stroke type which is comparatively simple of construction and yet peculiarly effective in operation.

The jack, as a whole, may be considered as novel from several aspects, while several 10 of the sets of coacting elements making up the jack, as a whole, are individually novel and may be embodied to advantage with sets of elements other than those here shown and particularly described.

15 Without attempting exhaustively to discuss the features of merit of the invention, for many of these will be self-apparent to those skilled in the art, I will outline briefly some of the outstanding features.

20 There are two general types of pump heads, one embodying a walking beam connection between the sucker rods and a power shaft, and the other embodying gear or rack and pinion connections between the sucker 25 rods and power shaft. Each type has its peculiar advantages; for instance, in the walking beam type, advantage is had of a crank action to secure the desirable effect of giving comparatively slow "pick-up" 30 movement to the sucker rods, that is, relatively slow movement at the lower end of the stroke when the load is initially taken by the pump plunger; while the rack and pinion type renders it possible easily to secure 35 a desirably long pump stroke. On the other hand, the walking beam type has the disadvantage of being undesirably limited as to stroke length and calls for special provisions to care for the variable angularity between 40 beam and sucker rods; while the usual rack and pinion type has the disadvantage of failing to provide for slow "pick-up" movement.

I have combined the walking beam and 45 rack and pinion mechanisms in such a manner that full advantage is had of the beneficial features of each type and yet the undesirable features of each type are eliminated. By my arrangement, the length of 50 stroke of the sucker rods is increased appreciably over the vertical extent of the walking beam stroke, and yet advantage is had of crank action to give variable speed or slow pick-up to the sucker rods.

55 The crank action, of course, slows down the stroke speed at each end of the stroke, or, in other words, as the rods are changing direction of movement at the stroke ends. However, it is desirable that the pick-up speed, that is the speed when the plunger 60 starts upwardly and first assumes its pumping load, be slower than the speed at the upper end of the stroke. Accordingly, I have provided means whereby this is accomplished. In a patent granted to me on December 22, 1925, on operating head for pumps, No. 1,566,692, I have shown means for accomplishing this slowing down of pick-up speed, but the means here disclosed 65 is distinctly novel, as compared with the means of the patent, and has many points of advantage thereover, as will be apparent from a consideration of the two. The means here employed will be set out fully in the following specification, and its description may be dismissed here by reference to it as a rack meshing with a gear of variable effective diameter. Viewed in one aspect, my invention may be considered as including an improved connection between a power shaft and a driven shaft through an oscillatory walking beam, and a novel connection between a driven shaft and the sucker rods whereby the rotary movement of the shaft imparts longitudinal reciprocatory or straight-line movement to the sucker rods. 70 However, either of these connections may be combined with connections other than those shown, and therefore may be considered as novel sub-combinations in themselves. 75

The mechanism includes a usual walking beam and a substantially vertically extending rack depending from the work end of said beam. By virtue of this substantially vertical arrangement of the rack, much complication is avoided, both as regards connections made thereto and means for guiding it through its movement. It is also advantageous in that it calls for no change of 80 the usual walking beam and actuating means therefor, either as regards its structural characteristics or disposition with relation to the wheel, it thus being possible quickly to shift from use of said beam for actuating the pump or for pulling or setting tubing or sucker rods. This vertical disposition of the rack also allows its employment to guide certain other elements of my device in their 85 movement, to obvious advantage.

My invention may be embodied with peculiar advantage in connection with duplex pumps, but this feature may be discussed to better advantage in connection with the 5 following detailed description.

As an important feature of my invention, the device is such that it is capable of being built sturdily and of being operated with minimum care and attention, both these 10 characteristics being very important due to the severe service conditions met in the field.

Other objects and novel features of the invention will be made apparent in the following detailed description, wherein reference is made to the accompanying drawings, in which:

Fig. 1 is a side elevation of an installation embodying my invention;

Fig. 2 is a view of Fig. 1 as viewed from 20 the right thereof;

Fig. 3 is a fragmentary section on line 3—3 of Fig. 1;

Fig. 4 is a fragmentary section on line 4—4 of Fig. 2;

25 Fig. 5 is a variational embodiment of the invention;

Fig. 6 is a section on line 6—6 of Fig. 5; and

30 Fig. 7 is a section on line 7—7 of Fig. 5.

In Fig. 1 numeral 10 designates a usual derrick floor supporting a usual Samson post 11 carrying walking beam 12. Walking beam 12 is adapted to be oscillated from power shaft 13 through usual crank 14 and pitman 15. The string of sucker rods 16 carries at its lower end a usual pump plunger (not shown) there being mechanism intermediate beam 12 and rods 16 whereby oscillatory movement of the beam imparts rectilinear reciprocatory movement to the rods. 35

40 On floor 10 are the horizontally spaced base members 17 between which extends the substantially vertical beam-rack 18, said rack having any suitable pivotal connection 45 with beam 12, the connection preferably being of a type allowing easy assembly or disassembly so the beam may be readily applied to uses other than as a pump-rod reciprocator.

50 A spur gear 20 is carried on shaft 21 which extends between and is journaled in supports or bases 17, and rack 18 is held in mesh with this pinion by such means, for instance, as the flanged guide rollers 22 on the base-supported shafts 23. Rack 18 extends through an opening 24 in floor 10, and it will be seen that while it is held between gear 20 and roller 22 it is capable of slight oscillatory or pivotal movement about connection 19 in order to compensate for the horizontal component of beam-end movement during beam oscillation. However, it will be understood that such compensation may be accomplished in other ways such as by providing 55 a lost-motion connection between beam and

rack and guiding the rack through a true straight-line path. Such variations are not shown for the reason that they will be readily understood by those skilled in the art and are merely equivalent to the showing here 70 made.

It will be seen that due to the crank drive of rack 18 said rack is adapted to be moved at variable speed while shaft 13 is moved at constant speed, the speed of the rack at each 75 end of the stroke being slower than that at the middle of the stroke, it following that the same condition will prevail throughout the mechanism driven from said rack, this being a desirable feature inasmuch as it is 80 imparted ultimately to sucker rods 16 whereby their speed of movement is decreased at the stroke ends, the desirability of this condition being well known to those skilled in the art. 85

Shaft 21 carries at its opposite extremities gears 25, these gears being generally characterized as of variable effective diameters. Before a detailed discussion of these gears, it may be stated that they are in operative 90 engagement with rod-racks 26 which, in turn, are connected to rods 16. Due to the variable effective diameters of gears 25 it will be seen that with shaft 21 revolving at given speed, racks 26 and hence rods 16 will 95 be driven at variable speed, and the assembly here is such that the variation in speed occurs while rods 16 are near the lower end of their stroke, the racks 26 and rods 16 moving more slowly at the lower end of their stroke than they do at the upper end thereof. 100

While any of the well known means may be employed for holding the variable diameter gears and their racks in mesh, it is preferable that the rack be held to straight 105 line movement rather than swinging to and fro as is true of one type of connection, it following that the pitch line P of the rack teeth 26^b will be curved to follow the variable diameter pitch circle of the gear, flanged 110 rollers 27 on support 17 holding the racks to the gears.

While the variation in diameter of the gears 25 may be made to suit individual requirements, a typical variation is illustrated 115 in the drawings wherein the pitch radius throughout an extent *a* of about 90° is constant and relatively long, the pitch radius throughout an extent *b* adjacent extent *a* and of about 160° is of gradually diminishing length, and the pitch radius through extent *c* adjacent extent *b* and of about 30° is of constant and relatively little length. The remaining angular extent *d*, which is ineffective and may be untoothed, leads from extent *a* to extent *c*. However, the ratio between spur gear 20 and the effective or toothed portion of a given gear 25 is such that with the stroke of rack 18 of given 120 length, the stroke of rack 26 will be of 125 130

greater than given length, a relatively long stroke thus being gained even though a walking beam, inherently limited as to stroke length, is employed. The gears 25 are so disposed on shaft 21 that their extents of diminishing radii lengths engage the rack while rods 16 are near the lower end of their stroke, while the extents *c* of relatively short, uniform length radii engage the rack while the change in direction of rod movement is being accomplished. It follows that the desirable slow pick-up movement of the rods and plunger is accomplished, whereas the rods are moved with comparative high speed during the remainder of the stroke, though they slow down somewhat as they reach and return from their upper limit, due to the crank connection.

Racks 26 preferably are connected by a cross head 28 which extends close to rack 18, this relative disposition enabling me to employ said rack as a means for guiding or aiding such means as roller 27 in guiding racks 26 through their vertical movement and thus eliminating the necessity of other guide means, to obvious advantage. For this purpose I have mounted a central clevis or yoke 29 on cross head 28, the arms 30 of said clevis extending across opposite sides of rack 18, and, with the clevis-carried guide rollers 31, defining a way 32 through which said rack extends, it being understood that due to the ratio of gears 20, 25, the racks 18 and 26 have relative longitudinal movement during beam oscillation.

Where rack 18 is allowed oscillatory movement to compensate for beam movement, the faces 33 of the rack, which faces engage rollers 31, may have such longitudinal contour that the racks 26 are maintained in substantially erect condition in spite of this oscillatory movement of rack 18.

While connection between racks 26 and rods 16 may be made in any suitable manner, it may be accomplished readily through cross-head 28, the rod extending upwardly through a central way 34 in said head and clevis or yoke 29. A suitable clamp 35 may be applied to rod 16^b at a point above head 28, but preferably, though not necessarily, said rod is not held against movement upwardly through said head. By reason of this provision, while clamp 35 provides a downwardly facing shoulder against which the head contacts to lift the rods positively, in the event the pump should become sanded in and hence, with its rods, resist downward movement, head 28 and its associated parts may move downwardly with respect to said rods, and damage to the mechanism thus avoided.

In Figs. 5, 6 and 7 I have shown the application of my invention to a pump of the duplex type. This embodiment may include the identical structure shown in Fig. 1 with

the addition of certain duplicate elements. Therefore, the structure similar to that shown in Fig. 1 is numbered similarly and need not be discussed again and such parts as are added and mere duplicates are given the same numeral but with the exponent "a."

Thus, there is provided, in addition to the elements shown in Fig. 1, a second pair of variable diameter gears 25^a with which racks 26^a are held in mesh by flanged rollers 27^a. Since rack 18 is not here available as a guide, I have provided a vertical guide post 37, braced from post 11 by horizontal member 38, cross head 28^a carrying a clevis 29^a, the arms 30^a of which, together with the arm-carried rollers 31^a define a guide-way 32^a to receive post 37. Sucker rods 16^a are connected to cross head 28^a in the manner described in connection with rod 16 and head 28, and is adapted to be connected to a usual plunger (not shown).

Racks 26^a engage gears 25^a at a point diametrically opposite that at which gears 25 engage racks 26, and gears 25 and 25^a are so relatively arranged that when rods 16 are full-down, rods 16^a are full-up, to an obvious end.

There is a feature about this combination which amounts more than to the mere duplication of timed, reciprocating elements, this feature being one of real advantage and one which would not be true were gears 25 and 25^a of uniform diameter, throughout. To make this point clear, consider Fig. 5. Rod 16 is at the lower end of its stroke and is about to pick-up the load, a time when an abundance of applied power is desirable. At the same time, rod 16^a is at the upper limit of its stroke and racks 26^a are engaging the relatively long-radius portions of gears 25^a. That is, while the effective portions of racks 26 are relatively close to shaft 21, the effective portions of racks 26^a are relatively distant from said shaft and hence have considerable mechanical advantage. This advantage is put to use inasmuch as the weight of racks 26^a, rod 16^a, and the column of oil (not indicated) above the pump plunger (not shown) applied to that rod is effectively brought to bear on gears 25^a in a manner tending to rotate gears 25^a and hence shaft 20 and gears 25 in a direction proper to lift racks 26 and rods 16, this lifting aid being given at the critical time, that is, as the load is being picked up by rods 16.

It will be understood the drawings and description are to be considered merely as illustrative of and not restrictive on the broader claims appended hereto, for various changes in design, structure and arrangement may be made without departing from the spirit and scope of said claims.

I claim:

1. In combination, a walking beam, means for oscillating the beam, a string of sucker

rods to be reciprocated, a substantially vertical rack depending from the work end of the beam and adapted to be reciprocated by oscillations thereof, means for guiding the 5 rack during its reciprocation, a second reciprocating rack connected to the sucker rods, and substantially paralleling the first mentioned rack, a pair of drivingly connected gears, one in mesh with each rack, 10 whereby reciprocation of the first mentioned rack rotates its associated gear in a manner to rotate the other gear and thereby reciprocate the second mentioned rack and the sucker rods, and coacting means between the 15 racks whereby the second mentioned rack is guided during its reciprocation by said first mentioned rack.

2. In combination, a walking beam, means for oscillating the beam, a string of sucker 20 rods to be reciprocated, a substantially vertical rack depending from the work end of the beam and adapted to be reciprocated by oscillations thereof, a second reciprocating rack connected to the sucker rods, an operative 25 connection between the racks whereby reciprocation of the first mentioned rack reciprocates the second mentioned rack and

thereby imparts longitudinal movement to the rods, said last mentioned connection including a pair of drivingly connected gears, 30 one in mesh with each rack, whereby reciprocation of the first mentioned rack rotates its associated gear in a manner to rotate the other gear and thereby reciprocate the second mentioned rack and the sucker rods, one 35 of said gears being of variable effective diameter.

3. In a power head for reciprocating two sets of pump rods, a shaft, means for rotating said shaft, a pair of gears on the shaft, 40 each gear being of variable effective diameter, and a pair of racks arranged at opposite sides of the shaft and held, one each, in mesh with said gears and operatively connected, one each, to said rods, a portion of 45 one gear having relatively large diameter being in mesh with its associated rack when a portion of the other gear having relatively small diameter is in mesh with its associated rack.

In witness that I claim the foregoing I have hereunto subscribed my name this 2nd day of December, 1926.

JOHN T. PHIPPS.
